Primary Examiner — T. Chase Nelson(74) *Attorney, Agent, or Firm* — Fredrikson & Byron, P.A.(57) **CLAIM**

The ornamental design for a sole for footwear, as shown and described.

DESCRIPTION

FIG. 1 is a bottom perspective view of a sole for footwear showing my new design;

FIG. 2 is a bottom view thereof;

FIG. 3 is a left side view thereof;

FIG. 4 is a right side view thereof;

FIG. 5 is a front view thereof;

FIG. 6 is a rear view thereof; and,

FIG. 7 is a top perspective view thereof, showing the sole for footwear as part of a footwear.

The broken lines showing a footwear in FIG. 7 is included for the purpose of illustrating the sole for footwear in use, and form no part of the claimed design.

1 Claim, 6 Drawing Sheets(56)
